UNITED STATES PATENT OFFICE.

WILLIAM GILLINGHAM, OF LITTLETON, WEST VIRGINIA.

FOLDING CRATE.

1,143,532.

Specification of Letters Patent. Patented June 15, 1915.

Application filed May 16, 1911. Serial No. 627,460.

To all whom it may concern:

Be it known that I, WILLIAM GILLINGHAM, a citizen of the United States, residing at Littleton, in the county of Wetzel and State of West Virginia, have invented new and useful Improvements in Folding Crates, of which the following is a specification.

The invention relates to crates, and more particularly to the class of folding shipping crates.

This invention relates to detachable tops for crates and more particularly to a door mounted for slidable movement within the top, the primary object of the invention being the provision of a detachable top wherein in the slidable door is so arranged that upon slight movement to either side of its normal position, an opening will be exposed having an area great enough to allow the entrance of live stock.

In the drawings: Figure 1 is a side elevation of a crate constructed in accordance with the invention, shown in upright position. Fig. 2 is a top plan view. Fig. 3 is a vertical longitudinal sectional view through the crate. Fig. 4 is a vertical transverse sectional view of the crate folded. Fig. 5 is a top plan view of the crate folded. Fig. 6 is a fragmentary perspective view of the top section, looking toward its inner or bottom face.

Similar reference characters indicate corresponding parts throughout the several views of the drawings.

Referring to the drawings by numerals, the crate comprises a bottom 5, preferably solid, although the same may be slatted in the ordinary well-known manner, and has fixed at opposite ends thereof strips or ledges 6 which rise vertically a distance from the inner face of said bottom. To these strips or ledges 6 are connected inwardly foldable end sections 7, the same being connected to said strips or ledges 6 by means of hinges 8, whereby said end sections may be swung inwardly toward and outwardly from the bottom, and connected to the bottom 5, at opposite longitudinal side edges, are inwardly foldable side sections 9, the same being connected thereto by means of hinges 10, whereby the said side sections may fold inwardly toward and outwardly from the said bottom, the side sections, when folded inwardly onto the bottom, are adapted to lie beneath the end sections 7 when folded.

Secured to the under face of the bottom 5, at opposite longitudinal edges thereof, are runner cleats 11, which, when contacting with the ground, will hold the bottom 60 slightly raised therefrom, the cleats being also designed to reinforce the bottom and protect it from damage when the crate is being transported from one point to another.

Secured to the corners of the end and side sections 7 and 9 are metal corner clips 12, which strengthen the said sections, the latter being composed of united longitudinal and transverse slats. The side and end 70 sections, medially of the inner longitudinal slats, are formed with recesses 13, in which are fitted coiled springs 14, the ends of the springs being connected to the sections, cross strips, and bottom respectively, and 75 are designed to automatically swing the said sections outwardly, after the same have been folded on removal of the top section, as will be presently described.

Formed medially in the end sections, at 80 the top edges thereof, and also near opposite ends of the side sections, at the top edges thereof, are sockets 15, in which detachably engage depending pins 16 fixed in the removable top section 17, comprising a frame 85 18, including spaced inner longitudinal slats 19 and spaced transverse slats 20, united thereto, the intermediate pair of transverse slats 20 being cut away to form an elongated door opening 20', in which is 90 disposed a slidable door 21, in the upper face of which are mounted guide eyes 22, the latter slidably engaging spaced parallel guide wires 23 disposed longitudinally across the upper face of the removable top section, 95 the ends of the guide wires being suitably secured at opposite ends of the said removable top section. Thus, it will be seen that the door 21 will have its outer face flush with the outer faces of the cross slats of the 100 removable top section, and is capable of being slid in the door way for the opening and closing thereof, so that poultry may be introduced into and removed from the crate, when set up in a convenient manner.

Pivoted to the inner longitudinal slats 19 are pivoted keeper members 24, which are adapted to be swung into engagement with the door 21 for locking the same, as any movement of the door brings certain sides 110 of the slats forming the door into contact with certain sides of the keeper members.

5   Mounted in the frame 18 of the removable top section 17, on opposite side bars thereof, are hook catches 25, which are adapted to engage in eye members 26 secured in the inner longitudinal slats of the side sections 9, when the latter and the end sections have been folded inwardly for securing the removable top section on the crate body, when in collapsed condition for compactness and 10 easy transportation thereof when not in use.

When the crate is in set up condition, these catches 26 are adapted to be brought into locked engagement with suitable eye members 27 carried by the outer longitudinal slats of the side sections 9, thereby fastening the removable top section in place on the crate body.

From the foregoing, taken in connection with the accompanying drawings, the construction and operation of the invention will be readily understood, without requiring a more extended explanation, and therefore, the same has been omitted.

What is claimed is:

25   A detachable top for crates including longitudinal and transverse slats secured together, a pair of rods passing over and secured to certain of said transverse slats, said top having an opening therein for allowing passage of live stock into the crate, a door 30 having slideable engagement with said rods and positioned in the opening, and keeper members pivoted to said top for holding said door in position, said door having a width approximately one-third the width of the said opening so that when the door is moved to either side of its normal central position a space will be exposed of an area great enough to allow the passage of live stock into the crate.

35   In testimony whereof I affix my signature in presence of two witnesses.

40   WILLIAM GILLINGHAM.

Witnesses:

CLEM YEATER,
R. W. REGER.
